UNITED STATES PATENT OFFICE.

HIRAM PLUMB AND SIMON H. PLUMB, OF HONESDALE, PENNSYLVANIA.

MORTISING-MACHINE.

Specification of Letters Patent No. 11,177, dated June 27, 1854.

To all whom it may concern:

Be it known that we, HIRAM PLUMB and SIMON H. PLUMB, of Honesdale, in the county of Wayne and State of Pennsylvania, 5 have invented a new and Improved Mortising-Machine; and we do hereby declare that the following is a full, clear, and exact description of the construction and operation of the same, reference being had to the annexed drawings, making a part of this specification, in which—

Figure 1, is a plan or top view of our improved machine. Fig. 2, is a side elevation of ditto. Fig. 3, is a longitudinal vertical section of ditto, the plane of section being through the center. The screw, chisels, and vibrating bar are not bisected.

Similar letters of reference indicate corresponding parts in the several figures.

20 This invention relates to a new and improved mortising machine, and consists in the employment or use of two chisels, for cutting the ends of the mortise, and a reciprocating chisel or planer, working horizontally for cutting out the wood between the two end chisels, as the latter are forced gradually into the wood.

To enable others skilled in the art to make and use our invention, we will proceed to describe its construction and operation.

A, represents a metallic frame, constructed in any suitable manner, and within which, a cutter stock, B, works, see Figs. 2 and 3, said cutter stock being of rectangular form, 35 and fitting between ways or guides, (a), (a), on the sides of the frames. The cutter stock is also hollow, similar to a box, and has arms, (b), at its upper part, with a nut, (c), at their top, through which nut, a screw rod, 40 C, works, see Fig. 3. The screw rod, C, extends upward through the top of the frame, A, and has a bevel wheel, D, upon it, see Figs. 1 and 3, into which a bevel pinion, E, upon a transverse shaft, F, gears, 45 see Fig. 1, said shaft running in suitable bearings, (d), (d), on the upper part of the frame, A.

G, G, Figs. 2 and 3, are two chisels which are secured by clamps, H, H, in the cutter stock, B, said clamps being constructed in any proper manner, and fitted within oblong slots, (e), in the sides of the cutter stock, so as to allow the chisels, G, G, to be adjusted nearer together or farther apart, 55 as desired.

I, I, Figs. 2, and 3, are stops attached to the upper part of the cutter stock. The stops are attached to the cutter stock by means of nuts, (f), which work on arms, (g), attached to the stops, said arms passing through an oblong slot, (h), in the side of the cutter stock, see Fig. 2. This attachment allows the stops to be adjusted in the cutter stock, similar to the chisels, G, G.

J, is a rectangular bar, which passes longitudinally through the cutter stock, B, as shown in Figs. 2 and 3.

K, is a chisel or planer attached to the lower end of a shank, L, said shank being secured by a pivot, (i), to the bar, J, as shown in Fig. 3. The upper part of the shank L, projects some distance above the top of the cutter stock, see Figs. 2, and 3. Two shoulders, (j) (j), are on the sides of the shank, L, immediately below the bar, J, 75 as shown in Fig. 3.

M, Figs. 1, and 2, is a crank attached to one end of the transverse shaft, F; and N, is a connecting rod which is attached to the crank, M, and a curved slotted arm, O, 80 which is at one end of a shaft, P, see Figs. 1, 2, and 3. At the opposite end of the shaft, P, there is a crank, Q, which is attached to a slide, R, which fits within a guide bar, S, attached to one end of the bar, J, see Figs. 1, 85 and 2. Upon one end of the shaft, F, there is a crank, T, by which the machine is operated.

Operation: The machine is secured upon the piece of timber by means of any proper clamp, and in such a position as to cause the mortise to be cut in the desired place. Motion is then given the crank, T, which causes the shaft, F, to rotate, and the bevel pinion, E, gearing into the bevel wheel, D, 90 causes the screw rod, C, to rotate, which, in consequence, forces downward the cutter stock, B, and the chisels, G, G, gradually penetrate the wood, and cut the ends of the mortise, while the crank, M, connecting rod, 100 N, slotted arm, O, and crank, Q, give a reciprocating motion to the bar, J—the slide, R, working in the guide, S. The chisel or planer, K, consequently has a horizontal reciprocating motion given it, as its shank, 105 L, is attached to the bar, J, and the wood between the two chisels, G, G, is cut or planed out in a smooth and even manner.

By having the shoulders, (j), (j), on the shank, L, some little distance below the bar, 110

J, a degree of play, or vibration, is given to the shank and chisel on planer, K, and the cutting edges of the chisel, K, have a tendency to penetrate the wood in the direction 5 of its course, see Figs. 2, and 3, in which the inclination of the chisel or planer is distinctly shown. The chisel or planer, K, it will be understood cuts while going in either direction, and the opposite inclination is 10 given said chisel, K, when at the end of its stroke by the stops, I, I, which act against the upper part of the shank, L. The planer or chisel, K, descends with the same speed as the chisels, G, G, as the bar, J, passes 15 through the cutter stock, and consequently, always has the same relative position to the cutters, G, G.

The edges of the chisels, G, G, should be a trifle below the cutting edge of the chisel 20 or planer, K, in order to insure the clean cutting of the ends of the mortise. The length of the vibration of the chisel or planer, K, is regulated by securing the connecting rod, N, higher up, or lower down on 25 the arm, O.

Different sized chisels may be employed according to the width of mortise desired, and the mortise may be made of the required 30 length, by adjusting the chisels, G, G, accordingly, in the cutter stock.

When the mortise is cut, the connecting

rod, N, may be detached from the crank, M, and a reverse motion given the crank, T, in order to elevate the cutter stock, B.

By the above machine, large mortises may 35 be cut with great facility, and about as rapidly as a workman can bore with an auger. The machine is simple, not liable to get out of repair, and works admirably well 40 in practice. In framing, much labor will be saved by its use, especially in large work.

We do not confine ourselves to the precise construction or arrangement of the parts herein described, for various modifications 45 may be employed for effecting the same purpose.

What we claim as new therefore, and desire to secure by Letters Patent, is:

Cutting mortises, by having two chisels, G, G, forced gradually into the wood or 50 stuff, and a reciprocating chisel or plane, K, working between. The chisels, G, G, cutting the ends of the mortise, and the chisel or planer, K, cutting out the wood between them, the above parts being arranged and 55 operated as herein shown, or in an equivalent manner.

HIRAM PLUMB.

SIMON H. PLUMB.
